UNITED STATES PATENT OFFICE

170,326

DOLL

Pearl M. Mathews, St. Louis, Mo.

Application August 4, 1952, Serial No. 20,888

Term of patent 3½ years

(Cl. D34—4)

To all whom it may concern:

Be it known that I, Pearl M. Mathews, a citizen of the United States, residing in the city of St. Louis and State of Missouri, have invented a new, original, and ornamental Design for a Doll, of which the following is a specification, reference being had to the accompanying drawing, forming a part thereof.

In the drawing:

Fig. 1 is a front elevational view of a doll embodying my novel design;

Fig. 2 is a top or plan view, and

Fig. 3 is a vertical sectional view as taken along line 3—3 of Fig. 2.

The rear view of the doll is identical to the front view thereof as shown by Fig. 1, except for omission of the face of the figure.

I claim:

The ornamental design for a doll, substantially as shown and described.

PEARL M. MATHEWS.
